UNITED STATES PATENT OFFICE.

FRANK HORODYSKI, OF RAHWAY, NEW JERSEY.

FOLDING BRUSH.

1,186,400.

Specification of Letters Patent. Patented June 6, 1916.

Application filed January 28, 1916. Serial No. 74,873.

To all whom it may concern:

Be it known that I, FRANK HORODYSKI, a citizen of the United States, residing at Rahway, in the county of Union and State 5 of New Jersey, have invented new and useful Improvements in Folding Brushes, of which the following is a specification.

This invention contemplates the provision of a device in the nature of a brush especially designed for cleaning bottles or other 10 like receptacles.

More specifically stated, the invention embodies a frame including pivotally connected side and end brush carrying members, associated with an operating element 15 whereby said members can be held in extended position within the bottle for cleansing the latter, and automatically collapsed to permit of the device being easily and 20 quickly inserted within or removed from the latter when desired.

While the essential characteristic features of the invention are necessarily susceptible of modification, still the preferred embodiment of the invention is herein illustrated, 25 in which:—

Figure 1 is a view showing the device in position for use within a bottle. Fig. 2 shows the device collapsed. Fig. 3 is a sectional view taken on line 3—3 of Fig. 1.

Referring more particularly to the drawing 5 indicates a tubular casing within which is slidably mounted the operating rod 6, the latter being associated with the brush frame in the manner to be presently described. The frame as shown in this particular instance includes parallel side brush carrying members 7 which are pivotally connected with upper and lower end members 8 and 9 respectively which are also provided 35 with bristles similar to those associated with the side members 7. Both the upper and lower members 8 and 9 respectively comprise two sections, the adjacent ends of the sections of the lower member being pivotally connected with the lower end of the operating rod 6 while the adjacent ends of the sections of the uppermost member 8 are extended through diametrically opposed elongated slots 10, formed in the tube 5, and are pivotally connected with the operating rod 6 at a suitable point in its length. It will be noted that the casing 5 is open at both ends, and by reason of the manner in which the 55 frame is connected with the rod, the frame is permitted to collapse upon elevation of

the rod 6, the side members 7 being drawn close to the casing 5 while the upper and lower end members 8 and 9 respectively are caused to assume a substantially inverted V-shaped position when the frame is collapsed. In this condition the sections of the lower member 9 move an appreciable distance within the lower end of the casing 5, while the slots 10 permit the sections of the upper member 8 to assume the position shown in Fig. 2.

The operating rod 6 is passed through an apertured lug 12 fixed within the casing, and interposed between the lug 12 and a collar or nut 13 mounted upon the rod, is an extensible spring 14, which latter operates to automatically collapse the frame in the manner shown, when pressure is released from the operating rod 6. The latter is provided 75 with a head or knob 16 which projects above the upper end of the casing 5.

In practice, the device in a collapsed condition as shown in Fig. 2 is inserted within the bottle or other receptacle to be cleansed, 80 subsequent to which the first and second fingers engage the finger grips 17 formed on the upper end of the casing 5, thereby bringing the palm of the hand above the knob 15 of the operating rod, whereby the latter can 85 be easily depressed against the tension of the spring 14, thereby moving the component parts of the frame to extended position for use in the manner shown in Fig. 1. Obviously, by the provision of the finger grips 17 and the manner in which the device is held 90 in the hand of the operator, a firm grip may be obtained upon the casing and operating rod, with a view of holding the frame extended against the tension of the spring 15, 95 while using the device. When it is desired to remove the device from the bottle or the like, pressure is removed from the operating rod 6 whereupon the spring 15 acts to elevate the rod and automatically collapse the 100 frame in the manner shown. The device can then be easily removed from the bottle, and provides a comparatively small article which will occupy but a minimum amount of space.

It is believed that from the foregoing description the nature and advantages of the invention will be readily understood without requiring a more extended explanation, although it is desired to have it understood 105 that any suitable material may be employed in the production of the device, and that the size of the various parts and their minor

details may be changed when desired without departing from the spirit of the invention.

What is claimed is:—

- 5 A device of the class described comprising in combination a tubular element having diametrically opposed slots opening at its lower end, and at a point adjacent the upper end thereof, a fixed lug arranged within said element, an operating rod slidably fitted within said element and through said washer, a collar mounted upon said rod, a spring encircling said rod and bearing against the said lug and collar to hold said rod normally elevated, a frame composed of pivot-
- 10
- 15

ally connected parallel side and end brush carrying members, said end members consisting of sections, the adjacent ends of which extend through said slots and are pivotally connected with said rod, whereby the 20 component parts of said frame may be extended or collapsed upon adjustment of said rod.

In testimony whereof I affix my signature in presence of two witnesses.

FRANK HORODYSKI.
